WATER CLOSET

Frank Reginald Dickinson, Carshalton, England

Application October 30, 1933, Serial No. 695,915
In Great Britain November 16, 1932

5 Claims. (Cl. 4—144)

The object of this invention is to provide means in connection with a water closet whereby the noise created during the flushing of the pan can be silenced.

5 For the purpose of my invention I provide a sliding panel, door or the like in connection with the pan or appliances fitted thereto, such panel being connected by suitable mechanism with the fold down cover, so that on lifting the cover, the 10 sliding panel is moved free of the opening of the pan and on a closing of the cover, the sliding panel will be moved to cover the opening of the pan and close same, whereby the noise of the flushing will be greatly reduced, and this silencing can be further attained by providing the 15 cover with a rubber or other cushion which rests on the seat.

My invention will be clearly understood from the following description aided by the annexed 20 drawings which illustrate two examples of carrying my invention into effect, and in which the panel is moved by mechanism connected with the cover of a seat of a water closet, but it must be understood that other means or mechanism for 25 actuating the panel may be employed.

Figure 1 is a side sectional elevation of a closet pan with the cover open and actuating mechanism in position with the sliding panel in the non-operative position.

30 Figure 2 is a similar view to Figure 1, but showing the mechanism in position, and sliding panel sealing the pan with the cover closed.

Figure 3 is a plan of Figure 1.

Figure 4 is a plan view of the actuating mechanism showing its position when the sliding panel is in the non-operative position.

Figure 5 is a side sectional elevation of a modified construction.

According to Figures 1 to 3, the pan 10, is constructed at its upper or flushing rim portion 11 with the back portion 12 having its rear edge straight, and through this back portion 12 is formed a slot or opening 13 coinciding with a groove in the inside wall of the rim portion 11, the opposite sides of which groove run parallel to about the centre of the opening of the pan 10, and then continue in a curve around the inside front edge of the rim 11.

Instead of the front portion being curved, it 50 may be any other shape, and the front of the panel shaped accordingly.

This groove is preferably lined with a strip 14 cemented therein.

At the back of the pan 10 underneath the slot 55 13 are positioned brackets 15, 15 carrying guide

rails 16, 16, these being positioned in line with the bottom of the groove and slot.

17 is the usual seat hinged at 18 as usual to the frame 19 which extends behind the pan 10.

At a line above the hinge 18 the cover 20 is hinged at 21 to the seat frame 19.

The panel 22 comprises a sheet of glass or other material of a width to fit the strip 14 of the groove and shaped at one edge to fit the front portion of the strip 14, and its back edge carries a bracket 23 to which is connected collapsible and extensible mechanism known as lazy-tongs, and comprising two rods 24, 24, extending from the bracket and each pivotally carrying at its end another rod 25, 25, these being positioned in a reverse direction to the rods 24, 24, and connected at their ends to ends of rods 26, 26 pivoted together at their centres, the other ends of these rods being pivotally connected to other rods 27, 27 pivoted together at their other ends to a bracket 28 fixed to the frame 19.

To the pivots of the ends of the rods 26, 27 are pivotally connected other rods 29, 29, and these are pivotally connected together at their free ends and to a bracket 30 connected by a link 31 with a bracket 32 on the top side of the cover 20.

The bracket 30 is slidable in a slot 33 cut in the frame 19.

In action and assuming the cover, mechanism and panel are in the position shown at Figure 1, the pan being open, on the lowering of the cover 30 the link 31 will pull on the rods 29 and tend to straighten them, and these in turn will open out the rods 27 and at the same time open out the cross rods 26, and these in turn will open out the rods 25 which will draw together the rods 24, and in so doing the distance between the outer ends of the rods 24 and the bracket 28 will be shortened, and the panel 22 will be moved along the groove to seal the pan as shown at Figure 2, 40 and a lifting of the cover will effect a reverse movement of the rods and draw the panel back clear of the opening in the pan as at Figure 1.

According to Figure 5, instead of forming the groove and U strip in the flushing rim 11 of the 45 pan 10, I may form such rim and slotted rear portion as a separate article 11a and affix same to the top of the flushing rim 11 of a closet pan and in other respects the construction is the same.

The cover may also be provided with overbalance weights or other devices to normally close the seat when the seat is unoccupied.

As a further security in preventing the noise of flushing issuing from the pan the under part of the seat as also the underpart of the cover 55

may be provided with a soft rubber ring to contact with the flushing rim or separate rim and the seat, and thus further assist in silencing the sound.

5 I may connect the cover or the seat or the operating mechanism by chain or otherwise, with the valve lever of the flush cistern, so that the valve may be actuated to flush the pan on the movement of the cover, seat or mechanism on 10 closing the panel.

What I do claim as my invention and desire to obtain by Letters Patent is:—

1. In a water closet having a flushing pan provided with an opening at the top thereof and a 15 movable cover for said pan opening, a closure member slidable rectilinearly transversely of said pan opening to open and close it, an element slidable in the rear of the cover, a connection from said element to the top of said cover, and extensible and contractible means connecting the 20 element, said closure member and a fixed part operative to slide said closure member into position to close the pan opening to render the flushing operation noiseless through closing of 25 the cover and to slide said closure member into open position through opening of the cover.

2. In a water closet having a frame, a flushing pan provided with an opening in the top thereof and a cover for opening and closing said pan 30 opening, a closure member and a cooperative guiding groove provided with parallel sides in which said closure member is slidable directly into positions to close and open said pan opening, an element slidably mounted in said frame, a connection from said element to the top of said cover, and extensible and contractible means connecting 35 said element, closure member and frame operative to slide said closure member in said groove

into position to close said pan opening through closing of the cover and thereby seal the pan opening, and to slide said closure member into open position with respect to said pan opening through opening of the cover and thereby uncover the pan opening.

3. In a mechanism for sliding a closure of a pan to and from open and closed positions through movement of a cover to open and closed positions, a lazy-tong mechanism, anchoring means for a 10 part of said mechanism, rods extending forwardly from the rear of said mechanism connected to said closure, a slidable element connected to said mechanism, and a connection from said slidable element to the outer side of said cover. 15

4. In a mechanism for sliding a closure of a pan to and from open and closed positions through movements of a cover to and from open and closed positions, a frame having a slot, a lazy-tong mechanism, a bracket slidable in said 20 slot and connected to said mechanism, a connection from said bracket to the outer side of said cover, means anchoring a part of said mechanism, and means connecting a part of said mechanism to said closure. 25

5. In a mechanism for sliding a closure of a pan to and from open and closed positions through movements of a cover to and from open and closed positions, a frame having a slot, a lazy-tong mechanism, a bracket slidable in said slot, rods pivoted to said bracket and connected to separate pivots of said mechanism, a connection from said bracket to the outer side of said cover, means anchoring said mechanism at one end, and rods pivoted to the mechanism adjacent the other 30 end, the latter rods extending forwardly and being connected to the closure. 35

FRANK REGINALD DICKINSON.
